US00D594432S

(12) **United States Design Patent**
Yoon et al.

(10) **Patent No.:** **US D594,432 S**
(45) **Date of Patent:** **** Jun. 16, 2009**

(54) **PORTABLE TELEPHONE**

(75) Inventors: **Joon Ki Yoon**, Seoul (KR); **Hyun Seop Kim**, Kyungki-Do (KR); **Chang Hwan Hwang**, Kyunggi-do (KR)

(73) Assignee: **Samsung Electronics Co., Ltd.** (KR)

(**) Term: **14 Years**

(21) Appl. No.: **29/235,238**

(22) Filed: **Jul. 29, 2005**

(30) **Foreign Application Priority Data**

May 26, 2005 (KR) 30-2005-0017643

(51) **LOC (9) Cl.** **14-03**

(52) **U.S. Cl.** ..... **D14/138 AB**

(58) **Field of Classification Search** D14/191, D14/138, 147-148, 247-248, 144, 496, 156, D14/341-347; 379/433.01-433.13; 455/575.3, 455/566, 575.1, 556.1, 556.2, 90.3; D21/517; D16/208

See application file for complete search history.
